UNITED STATES PATENT OFFICE.

AMBROSE J. NICHOLS, OF NEW MARKET, NEW HAMPSHIRE.

RING-SPINNING FRAME.

SPECIFICATION forming part of Letters Patent No. 415,419, dated November 19, 1889.

Application filed July 15, 1889. Serial No. 317,541. (No model.)

To all whom it may concern:

Be it known that I, AMBROSE J. NICHOLS, of New Market, county of Rockingham, State of New Hampshire, have invented an Improvement 5 in Ring-Spinning Frames, of which the following description, in connection with the accompanying drawings, is a specification, like letters on the drawings representing like parts.

This invention has for its object to provide a ring-spinning frame with means whereby by bowing out of the yarn may be restrained and the yarn be softened, and at the same time drag be put upon the yarn to insure 15 better and more compact winding, and that without increasing the tension on the yarn at the rolls.

In accordance with my invention I have provided a spinning-frame with a yoke which 20 is located above the usual ring and traveler, the said yoke surrounding the bobbin, the feet of the yoke being attached to the ring-holder, so that the yoke may not only be adjusted in unison with the ring on the ring- 25 rail, but so that the said feet may act to keep the traveler clear.

Figure 1 shows a sufficient portion of a spinning-frame with my improvements added to enable my invention to be understood. 30 Fig. 2 is a top or plan view, enlarged, of my improved yoke mounted on a ring-holder; and Fig. 3 is a section in the line α , Fig. 2.

The rail A, upon which is secured the supporting case or holder B, to receive the foot 35 of the spindle C, shown as of the sleeve-whirl class, the ring-rail D, the ring E, the traveler f, the ring-holder h, the bobbin G, and the guide-eye H, are and may be all as common in ring-spinning frames of usual construc- 40 tion.

In accordance with my invention I have surrounded the bobbin above the usual ring with a separator-yoke a, having feet or legs a', which, as herein shown, are attached to the 45 ring-holder h, so as to be adjustable in unison with the holder and the ring on the usual ring-rail, to which rail the said holder in practice will be secured by usual screws, as 3, in the slots 4, one of the said screws being 50 shown in Fig. 1. The yoke is slotted, as at 5, the said slot being preferably diagonal, as

shown in Fig. 2, to enable the yarn y to be led readily to the inner side of the yoke, so that the yarn between the usual traveler and guide-eye may travel in the space between 55 the inner side of the yoke and bobbin and yet not escape, the said yoke acting to substantially completely surround the bobbin and prevent not only the bowing out of the 60 yarn, so as to hit against and break down the 65 yarns of adjacent spindles and bobbins, but also to prevent the escape of yarn outwardly through the yoke during the rotation of the spindle. The inner edge of the yoke (see Figs. 2 and 3) is provided with a series of inclined serrations or teeth resembling screw- 70 threads, the said teeth being inclined from top to bottom of the yoke, the upper ends of the teeth being inclined in the direction of rotation of the traveler. As the yarn is carried around inside the yoke in usual manner these teeth, owing to their inclined direction, produce a certain amount of drag upon the 75 yarn on its way to the traveler, the drag being almost entirely between the yoke and the traveler and not extending up to the rolls, the inclined teeth acting in a measure to lift on the yarn being carried over them or to screw the thread up toward the rolls, thus producing an increase of tension in the yarn at the 80 point where it winds upon the bobbin, and that without increasing the tension at the rolls. These serrations or teeth by their action upon the yarn also in a measure loosen the external fibers of the yarn, giving it an 85 appearance of mule-spun yarn, the serrations also clearing off any motes or imperfections in the yarn, thus leaving the same clear before its arrival at the traveler.

The legs of the yoke attached to the ring- 90 holder close to the line of travel of the traveler also act to keep the traveler clear of motes and lint.

I am aware that separators substantially semicircular in shape have been employed; 95 but a separator which does not surround the bobbin cannot act as does my improved yoke.

The yoke herein shown is represented as composed of sheet metal and its legs or sup- 100 porters integral therewith.

I do not broadly claim a yoke-shaped sep-

arator; but prior to my invention I am not aware that such a separator has ever been supported by a ring-holder or that such a separator has ever been provided with a series 5 of serrations at its inner edge to act as herein described, or that the legs supporting the yoke have ever been attached to a ring-holder and so located with relation to the ring and traveler thereon as to act as a clearer for the 10 traveler.

I claim—

1. The combination, with a spindle, a ring-rail, a ring-holder, a ring therein, and a traveler, of a separator-yoke *a*, secured to the 15 ring-holder and substantially completely surrounding the bobbin, to operate substantially as described.

2. The ring-rail, the adjustable ring-holder thereon, the ring in the said holder, the traveler, and the spindle, combined with the separator-yoke secured to the ring-holder and substantially completely surrounding the bobbin and supported at a distance above the ring, and provided with a series of inclined serrations to act upon the yarn as the latter 20 travels about the bobbin and inside of the yoke, as and for the purposes set forth.

In testimony whereof I have signed my name to this specification in the presence of two subscribing witnesses.

AMBROSE J. NICHOLS.
